C. F. SHERMAN.

EXPANDING ARBOR,

APPLICATION FILED JULY 11, 1919. RENEWED JUNE 7, 1920.

1,346,917.

Patented July 20, 1920.

Inventor:

Cortis F. Sherman,

By his Atty, C. L. Russell

UNITED STATES PATENT OFFICE.

CORTIS F. SHERMAN, OF HARTFORD, CONNECTICUT, ASSIGNOR TO HESS-BRIGHT MANUFACTURING COMPANY, OF PHILADELPHIA, PENNSYLVANIA, A CORPORATION OF DELAWARE.

EXPANDING ARBOR.

1,346,917.

Specification of Letters Patent.

Patented July 20, 1920.

Application filed July 11, 1919, Serial No. 310,088. Renewed June 7, 1920. Serial No. 387,158.

To all whom it may concern:

Be it known that I, CORTIS F. SHERMAN, a citizen of the United States, residing at Hartford, in the county of Hartford and 5 State of Connecticut, have invented certain new and useful Improvements in Expanding Arbors, of which the following is a specification.

This invention relates to arbors for rigidly supporting annular pieces of work, particularly those which are to be machined or worked upon in some manner, an object of the invention being to form the shell of such an arbor with a closed chamber and 10 locate and support a reciprocatory expander therein in such manner that the working parts are completely incased within such closed chamber, the expander positively guided and the shell and expander rigidly bonded together when the work seat is expanded for holding the work.

The drawings accompanying this specification illustrate one practicable embodiment of my invention, in which drawings—

25 Figure 1 is a view partly in central longitudinal section and partly in elevation of my improved arbor, showing the same in its work clamping or holding position.

Fig. 2 is a cross section taken on a plane 30 at about line 2—2 of Fig. 1, the expander being omitted.

Fig. 3 shows the expander in elevation, and

Fig. 4 is an end elevation from the left-hand end of Fig. 1.

The shell 5 of the arbor is formed with a hollow interior or closed chamber 6 and with a substantially cylindrical external work receiving face or work seat 7. This 35 face preferably has a slight taper from the shoulder or back stop 8 toward the outer or front end of the arbor. A piece of work in the present instance, the inner ring of a ball bearing, is indicated by dotted lines 9 in position on this work seat 7 and in engagement with the back stop 8.

This invention is an improvement on that 40 form of arbor in which a reciprocatory expander is incased within the chamber of a closed shell; the purpose of this invention being to positively guide and support the expander plug independently of its surface engagement with the shell and, as it were, to bond the entire structure together during 45 the forward or clamping movement of the

expander plug and afterward when the shell and work seat have been expanded and the piece of work securely held in position on the arbor. In using the terms backward and forward, front end and rear end, considerable confusion may arise owing to the fact that what is the processional movement of the expander is toward what is really the back end of the arbor and that the recessional or unclamping movement of the 60 plug is toward what is the front end of the arbor. With this brief explanation in mind it is believed that the apparent confusion will be obviated. The expander plug 10 is shown formed of considerable weight 65 in relation to its size and provided upon its exterior with a tapering face which mates with a suitably formed tapering face upon the interior of the shell of the arbor. The rear end of the shell is provided in the present illustration with an integral closure 11 having a central bore. The front end of the shell is provided in the illustration with a removable closure 12 provided with a central bore in alignment with the bore of the 70 integral closure 11. In these bores is rigidly supported a guiding bar 13, upon which is mounted for reciprocation the expanding plug 10, the plug being provided with an interior bore 14 of such dimensions relative to the bar 13 that it has a close working fit therein sufficiently free to permit the reciprocation of the expander, but also sufficiently close to prevent any lateral movement of the plug. In the illustration the 75 bar 13 is provided with an integral collar 15, the rear face of which engages the front face of the end closure 11 and is clamped thereto by a suitable heavy nut 16, having screw threaded engagement with an extending end of the bar. A disk of elastic material 17 is shown facing the end closure 12 for receiving the impact of the expander in its recessional movement. Lathe centers 18, 18, are provided in the ends of the bar 13. By this means the force of holding the arbor to the live spindle is carried directly by a solid part and in nowise interferes with the efficient action of the shell. The end 80 closures or more correctly, the end walls of the shell, have such a close fit with the bar 13 that the entrance of fluids or grit is practically impossible. The wall of the arbor shell illustrated in the drawing is so formed that although it is unbroken it is 85

90 95 100 105 110

capable of circumferential expansion and contraction, particularly under the influence of force applied from within the chamber of the shell, the expansion being caused by the 5 processional movement of the expander plug driving its tapering surface against the tapering wall of the shell, the contraction resulting from the natural elasticity of the metal of the shell when relieved from the 10 expanding force. In practice I have found it desirable to form a shell with a series of longitudinal external ribs 20 set off by a series of intervening grooves 21 and on the interior of the shell a series of longitudinal ribs 22 set off by a series of 15 intervening grooves 23. It will be noted that the grooves 23 are below, in a radial direction, the ribs 20 and that the ribs 22 are below, in a radial direction, the 20 grooves 21. It will also be noted that in cross section the interior grooves 23 are substantially half-circles at the deeper portion and that the grooves 20 are substantially 25 half-circles throughout, except at the enlargement, which affords the back stop face 8.

The taper face on the inner wall of the shell for the engagement of the taper face of the expander 10 is provided on the crests 30 of the ribs 22. This face, or rather, the series of faces, is represented by the reference character 24, Fig. 2. When it is desired to apply a piece of work, as for instance, the ring 9 of the arbor, the arbor is 35 preferably placed in an upright position with the back end, the nut 16 in the illustration, resting upon the work bench and the expander plug retracted from its shell expanding position. The ring is then 40 slipped over the outer or front end of the arbor and over the work seat 7 and preferably resting against the back stop 8. The arbor is then raised a short distance from the work bench and permitted to drop forcibly 45 against the bench or a block of wood thereon. The impact of this blow imparts the excursion or processional movement to the expander plug, causing this to advance against the taper seat 24 and move toward the rear 50 end of the arbor, guided nevertheless by the bar 13. The entire shell of the arbor and the plug are through the instrumentality of the bar thus completely bonded together in a rigid structure. The wall of the shell is 55 expanded, expanding the work seat against the work and holding this securely in position. It is obvious that any unevenness in the bore of the work carried on the work seat will not throw the arbor out of true when the plug is forced to this expanding position. It will also be obvious that pressure 60 applied to one side of the work carried by the arbor is evenly distributed throughout the entire structure without any tendency to 65 cause the working point of the work to pass

through an eccentric orbit. When it is desired to remove the work the arbor is taken from the centers and the front end, represented by the end wall 12, is permitted to drop upon the work bench or is given a 70 blow by some elastic body, the impact of which blow causes the recessional movement of the expander plug, drawing this toward the end represented by 12 and preferably against the cushioning member 17. The momentum imparted to the work by the impact of the blow causes this immediately upon the wall of the shell assuming its former position to fall off, whereupon a new piece of work is placed in position and the expanding 75 operation is repeated.

As the lathe centers 18 are formed in the extending ends of the supporting rod, it will be seen that when these become worn or injured, the arbor itself does not have to be 80 repaired or renewed but that the bar only requires repair or an interchangeable one 85 substituted in its place.

It is to be understood that the device shown in the drawing is illustrative of my 90 invention and that changes may be made within the scope of the claims without departing from the spirit thereof.

I claim as my invention:

1. An expanding arbor, comprising a shell 95 having elastic side walls, provided on the exterior with a work seat, the walls of the shell forming a closed chamber, a guiding bar carried by the end walls of the shell, and a weighted expander plug mounted on said bar for reciprocation within the chamber and adapted to act upon the elastic side walls for expanding the same and the work seat.

2. An expanding arbor, comprising a shell 105 having elastic side walls, provided on the exterior with a work seat, the walls of the shell forming a closed chamber, a guiding bar carried by the end walls of the shell, and a weighted expander plug mounted on said bar for reciprocation within the chamber and adapted upon its excursion to act upon the arbor for expanding the same, the parts being so organized that the impact of a blow 110 upon one end of the arbor effects the excursion of the expander.

3. An expanding arbor, comprising a shell 115 having elastic side walls, provided on the exterior with a work seat, the walls of the shell forming a closed chamber, a guiding bar carried by the end walls of the shell, and a weighted expander plug mounted on said bar for reciprocation within the chamber and adapted upon its excursion to act upon the arbor for expanding the same, the parts 120 being so organized that the impact of a blow upon one end of the arbor effects the excursion of the expander and the impact of a blow on the other end of the arbor effects 125 the recession of the expander.

4. An expanding arbor, comprising a shell, having rigid end walls, elastic side walls, and upon its exterior a work seat and a work stop at the back of the seat, the seat tapering from such stop toward the front, the wall of such shell forming a closed chamber tapering from the front and toward the back end, a guiding bar carried by the end walls, and a similarly tapering reciprocatory expander plug inclosed in said chamber and mounted on said bar.
5. An expanding arbor, comprising a shell, having rigid end walls, elastic side walls, and upon its exterior a work seat and a work stop at the back of the seat, the seat tapering from such stop toward the front, the wall of such shell forming a closed chamber tapering from the front end to-
- ward the back end, a guiding bar carried by the end walls and extending through the same and there provided with lathe centers.
6. An expanding arbor, comprising a shell, having rigid end walls, elastic side walls, and upon its exterior a work seat and a work stop at the back of the seat, the seat tapering from such stop toward the front, the wall of such shell forming a closed chamber tapering from the front end toward the back end, an interchangeable guiding bar carried by the end walls and extending through the same and there provided with lathe centers.

In testimony whereof, I have hereunto set my hand this 3rd day of July, 1919.

CORTIS F. SHERMAN.
